UNITED STATES PATENT OFFICE.

ALBERT PAUL COCHRANE, OF BROOKLYN, NEW YORK, ASSIGNOR TO HERVEY, BARBER & MCKEE, OF NEW YORK, N. Y., A FIRM COMPOSED OF EVERETT P. HERVEY, ARTHUR WILLIAM BARBER, AND LANIER MCKEE.

BOX OR CRATE FRAME.

1,326,646.

Specification of Letters Patent.

Patented Dec. 30, 1919.

Application filed August 6, 1917. Serial No. 184,582.

To all whom it may concern:

Be it known that I, ALBERT PAUL COCHRANE, a citizen of the United States, and resident of the borough of Brooklyn, in the county of Kings and city and State of New York, have invented a new and useful Box or Crate Frame, of which the following is a specification.

The object of this invention is to provide a box or crate frame composed of separate elements forming the uprights and longitudinal and transverse top and bottom members which may be rigidly fastened and braced at the apical corners to form a frame-work, which may receive suitable panels to form a container, or which may be assembled as a reinforcement around a complete box. This is accomplished by the combination of angle iron elements, the flanges of each of which form portions of two sides of a rectangular parallelepiped and which are interlocked at the ends, and clamping corner fastenings, each of which unites the ends of three irons at one of the apical corners.

In the accompanying drawings:

Figure 1 is a view, partly in side elevation and partly broken away and sectioned, of a container constituted by such a frame-work, with panels filling the open sides, and one of the corner fastenings removed. It is to be understood that the connection screw shown in the upper right-hand corner of this view is oblique and not parallel to the plane of the paper;

Fig. 2 is a perspective view of one of the corners without the fastener;

Fig. 3 is a plan of the same corner;

Fig. 4 is a side view thereof;

Figs. 5, 6 and 7 are plan views of blank ends corresponding to the corner joints of the preceding views; and

Fig. 8 is a perspective view of a different form of corner joint.

The frame comprises four uprights 2, four longitudinal members 3, two each at top and bottom, and four transverse or end members 4. Each of these members is an angle iron, or a strip of sheet metal bent longitudinally to form two flanges at right angles to each other. Thus, as shown, the flanges of each element lie in the planes of two sides of a rectangular parallelepiped, or over-

lie two faces of such a figure included within them.

The ends of three of these elements meet at each apical corner when the frame-work is erected, and are there held and braced by corner fastenings 5. In the preferred form these fastenings comprise each a pyramidal or virtually pyramidal cap 6, an inner member 7 formed to fit the internal corner, and a connection 8 disposed diagonally and centrally with respect to the solid angle of the parallelepiped, so as to draw the inner and outer member equally against the three meeting members. The said connections may be screw stems projecting outward from the inner members 7 centrally of the solid angles of the parallelepiped, and passing through openings in the apices of the caps 6, outside of which they are engaged by nuts 9, by turning of which the parts are clamped together. These nuts may be formed as rounded skidding bosses, as shown. Fastenings of this type, though of specifically different construction, are used in a different combination in my Patent No. 1,195,908, of August 22, 1916, and the particular form shown herein is included in my Patent 1,264,015, of April 23, 1918.

Fastenings of still other types may be employed.

The meeting ends of the angle iron elements are cut to present interfitting tongues and recesses, thereby causing the meeting flanges to lie in the same plane and securing the advantage of an interlock which keeps the irons from pulling apart. The particular shape of the formations may be widely varied. Figs. 2 to 7 show one of the possible constructions, wherein the flanges at the end of the member 3 are cut to present two wings 11 projecting laterally from the center ridge, these wings being triangular at the base and circular at the ends; the adjoining end of member 4 has a recess 12 in one flange corresponding to one of said wings, and the end of its other flange cut off at 13, leaving an oblique edge and a curved edge; the upper end of member 2 has a recess 14 in one flange receiving the other of the wings 11, and a lateral notch 15 in its other flange fitting the formation 13. In such a construction, it will be ob-

served that the ends of the several members are all different, which is a useful guide in assembling. In the simpler construction of Fig. 8 the ends are alike, one flange of each 5 having a longitudinal tongue 16 and a lateral recess 17, the tongues and recesses corresponding to each other and fitting as shown.

A container of crate can be formed from 10 the frame-work, by inserting suitable panels in the sides within the angle irons, which panels may be solid or not as desired. Preferably the panels are clamped between the inner members 7 and the interlocking 15 flanges of the angle irons, as shown.

What I claim as new is:

1. A box or crate frame comprising separate angle irons having interlocking formations at their ends keeping them from 20 pulling apart, and clamping corner fastenings each capable of holding the ends of three irons in the interlocking relation.
2. A box or crate frame comprising separate angle irons having interlocking formations at their ends keeping them from 25 pulling apart, whereby an apical corner is formed by three ends each of which inter-

locks with the other two, and a common clamping fastener for holding the three ends in the interlocking relation.

30

3. A box or crate frame comprising separate angle irons forming the uprights and longitudinal and transverse top and bottom members of the frame-work, the ends of said irons meeting at the apical corners having 35 their flanges cut with interlocking tongues and recesses keeping them from pulling apart, and clamping fastenings for the apical corners each comprising a corner cap and an inner member and a connection extending diagonally through the corner, whereby the members are held in the interlocking relation.

35

4. A box or crate frame comprising the combination of separate angle irons 45 constituting the frame elements, said elements having interlocking formations at their ends, apical corner clamping fasteners, each holding the ends of three irons in the interlocking relation and comprising inner and 50 outer portions and a diagonal connection, and panels also held by said fasteners.

ALBERT PAUL COCHRANE.
